UNITED STATES PATENT OFFICE.

CLARENCE A. PETERSON, OF WASHINGTON, DISTRICT OF COLUMBIA, ASSIGNOR TO
WELSBACH LIGHT COMPANY, OF GLOUCESTER CITY, NEW JERSEY, A CORPORATION
OF NEW JERSEY.

GAS-BURNER.

1,149,535.

Specification of Letters Patent.

Patented Aug. 10, 1915.

Application filed January 11, 1913. Serial No. 741,427.

To all whom it may concern:

Be it known that I, CLARENCE A. PETERSON, a citizen of the United States, residing at Washington, in the District of Columbia, have invented a new and useful Improvement in Gas-Burners, of which the following is a full, clear, and exact description, reference being had to the accompanying drawings, forming part of this specification, 10 in which—

Figures 1 and 2 are vertical sections taken in planes substantially at right angles to each other of a gas burner embodying my invention; Fig. 3 is a section on the line III—
15 III of Fig. 1; Fig. 4 is a side elevation of the burner; and Fig. 5 is a section on the line V—V of Fig. 1.

My invention relates to gas burners of the inverted incandescent type.

20 The object of the invention is to simplify and improve such burners, as well as to improve their appearance, and provide for a long unobstructed vertical passage for the products of combustion while shielding the 25 gas cocks, regulator, and pilot bypass within an air chamber extending across the casing. I also provide for ready accessibility to the bypass adjusting device, and also the adjustment for the gas regulator. I further provide for passing the stem of the gas 30 cock out through the air chamber and provide a burner of comparatively small size without reducing the light-giving capacity. The lamp may be made of such shape as to 35 readily harmonize with electric lamps when mounted on combination fixtures.

In the accompanying drawings, in which I have illustrated the preferred embodiment 40 of my invention and which will now be described, the numeral 2 designates the casing which is of bell shape, being open at its lower end and also at its upper end, except for the central raised portion 3, having the 45 depending parallel extension flanges 4. The raised central portion is provided with a central opening to receive therethrough the upper portion of the valve member 5. The outer casing is secured on the valve member by the collar 6, through which passes the set 50 screw 7, which acts as a bypass adjustment in the manner hereinafter described.

The numeral 8 designates the gas supply pipe which is connected to the valve member 5 by means of the connector 9.

55 10 is the main valve or cock of the turning

plug type and having its stem projecting outwardly through the casing for the attachment of a suitable actuating device. In the drawing, I have shown this device as consisting of a two-armed lever 11 with actuating chains 11^a attached thereto. The valve member 5 is formed with a bypass passage 12, around the valve 10, and leading to a small pipe 12^a which conveys the gas to the pilot burner. The entrance to the bypass passage 12 is controlled by the extended point 7^a of the screw 7, this point acting as a needle valve for regulating the amount of gas supplied to the pilot.

The numeral 14 designates a gas regulator 70 of any well known character which is screwed onto the lower portion of the valve member 7 and which has an adjusting screw 15, projecting laterally and terminating adjacent to an opening 16 in the casing 2. 75 This opening 16 provides means whereby the screw 15 is made readily accessible for adjustment.

The numeral 17 designates the usual mixing tube, which is screw-threaded to the regulator 14, and upon the lower end of which is threaded the burner tip support 18.

The air intake chamber which is located within the casing comprises the two vertical plate members 19, whose upper portions slide within the part 3 of the casing between the flange extensions 4 thereof. The space between these plate members is closed at the bottom by the plate 20, which has the depending outwardly flared skirt 21, provided with an inturned slotted flange 22, for supporting the usual inner globe (not shown) of the burner. The outer globe or shade of the burner is secured within the lower part of the casing by any suitable means, such as the usual screws 23.

The stem of the valve 10, the regulator-adjusting screw 15, and the pilot pipe 12^a are all contained between the two plates 19 of the intake air chamber. The latter is open at its sides and the body or casing 2 is provided with air intake openings 24, opposite these open edges. 25 is the spacing sleeve surrounding the lower part of the mixing tube and seated between the bottom plate 20 of the air intake chamber and a nut 26, against which the burner tip support 18 screws.

It will be seen that the spaces at opposite 110 sides of the air intake chamber provide un-

obstructed vertical flues of considerable length for the products of combustion, the latter escaping at the upper end of the casting at each side of the central portion 3 thereof. The construction and arrangement of the parts makes a very compact form of burner, without reducing its light-giving capacity, and further forms a burner of such shape that it will readily harmonize with 10 electric lamps when placed upon the same fixtures. The parts within the intake air chamber are protected from the direct action of the products of combustion, and all of the parts, with the exception of the valve-actuating connections, are inclosed within the burner body or casing.

I do not desire to limit myself to the precise construction and arrangement of parts which I have herein shown and described, 20 as it is obvious that various changes can be made in the details of construction and arrangement thereof, without departing from the spirit and scope of my invention, as defined in the appended claims.

I claim:

1. An inverted incandescent gas burner having a casing, an air chamber extending across the casing and having holes through the outside sides of the casing, a gas supply pipe leading to a mixer tube within the casing, and a shut-off cock, a gas regulator and a pilot tube all contained within said air chamber, substantially as described.
2. An inverted incandescent gas burner having a casing, an air chamber within the casing and extending to outside sides thereof

Copies of this patent may be obtained for five cents each, by addressing the "Commissioner of Patents, Washington, D. C."

leaving a vertical flue at each side of said chamber, a mixing tube within said chamber, and a vertical gas pipe leading to the mixing tube and having within said chamber a shut-off cock, a regulator having an accessible adjusting device, and a pilot tube, substantially as described.

3. An inverted incandescent gas burner, comprising a casing of general bell shape 45 and tapering upwardly, said casing being open at the bottom and having openings at its top, a plurality of partitions extending transversely across the interior of the bell inside the side thereof with openings at the 50 ends leading through the walls of said outer casing, said partitions in connection with a bottom member forming a closed air chamber with a vertical flue at each side thereof, a gas-mixing device within said chamber and 55 having air intake openings communicating with the chamber, a gas-supply pipe connecting to the mixing tube and having a shut-off cock provided with operating means extending through said chamber and to the 60 exterior of the casing, and a regulating valve below the shut-off cock and having adjusting means extending within the said chamber and accessible through the wall of said casing, substantially as described.

In testimony whereof, I have hereunto set my hand.

CLARENCE A. PETERSON.
